UNITED STATES PATENT OFFICE

WILLIAM H. MILLSPAUGH, OF SANDUSKY, OHIO, ASSIGNOR TO THE PAPER & TEXTILE MACHINERY COMPANY, OF SANDUSKY, OHIO, A CORPORATION OF OHIO

BLOWING PREVENTATIVE FOR PAPER-MACHINE FELTS

Application filed January 31, 1930. Serial No. 424,795.

This invention relates to means for use in paper-making machines to prevent blowing effects in connection with the deflection of paper-carrying felts.

5 In a paper-making machine, the imposition of the paper sheet on a travelling felt will entrain air between the paper and felt, and when the felt is drawn over or in engagement with a deflecting roll the pressure effect 10 on the felt and paper will compress the trapped air which, forcing its way between the paper and felt in advance of the point where the felt engages the roll, will cause the paper to puff or to leave the surface of the 15 felt. This effect, known as blowing, may be sufficiently pronounced to cause serious trouble in some cases, especially in high speed machines.

Similar difficulty is encountered where top 20 and bottom press felts are brought into co-action by a guide roll deflecting the course of either or both of the felts, in which case the paper sheet if carried by the felt engaging the roll may be blown from such felt as it 25 approaches the roll, or the sheet if carried by the other felt may be injured by being blown against its own felt by air entrained and compressed between the paper sheet and the felt in contact with the guide roll.

30 The object of the present invention is to prevent such blowing effects, in connection with the deflection of paper-carrying felts, by providing for escapement of the trapped air. This is accomplished by utilizing a 35 perforated hollow guide roll, interiorly open to the atmosphere, engaged by and deflecting the paper-carrying felt or one of co-acting paper-carrying felts, whereby the air trapped between the paper and the felt in 40 contact with the guide roll is forced out through the pores of the felt and the perforations of the deflector roll to the atmosphere. The deflector roll, suitably mounted to effect a desired deflection and thereby to impose a 45 pressure action against the taut felt and paper thereon may consist of a cylindrical shell having closely drilled perforations, similar for example to an ordinary suction 50 roll shell, so as to present a large number of

closely disposed orifices for the escapement of the air.

One illustrative embodiment of the invention is shown in the annexed drawing, in which:

55 Fig. 1 diagrammatically represents a paper-machine press section;

Fig. 2 is a detail representation of a press felt and co-acting perforated deflecting roll.

60 In the illustrated construction, the paper sheet 1, received from the wet end or other preceding section of the machine, is carried by the press felt 2 in contact with the top felt 3 between the co-acting top and bottom press rolls 4 and 5, and is delivered by the 65 felt 2.

70 The press felt 2 is engaged by the perforated hollow guide roll 6, which in this instance is located to bring the co-acting felts into co-action and to obtain a desired lap of the felts on the top press roll. By the pressure imposed by the deflecting roll against the felt and paper, the air trapped between the felt and paper over the roll is forced 75 therefrom through the felt 2 into the perforations of the roll, thus escaping to the atmosphere.

77 If in an arrangement of the type illustrated the paper sheet were carried by the other felt than that engaging the deflector 80 roll, the perforations of said roll would permit the escape to the atmosphere of air entrained between the sheet and the felt in contact with the roll, preventing such air from 85 being compressed and blowing the paper sheet against its carrying felt.

87 The felt 2 may be considered as representing any paper-carrying felt in any organization embodying the invention. It will be 90 understood that the foregoing description with reference to the specific embodiment selected for illustration is not to be taken as limiting the invention, which is generally applicable to and may be used in various locations in machines of both the cylinder and 95 Fourdrinier types or other types, and in machines for making either single-ply or plural-ply paper. For example, in a machine having co-acting felts to carry the paper through 100 the press, separately formed paper sheets

may be imposed on the respective felts and brought into contact with one another by the converging runs of the felts where they are brought into co-action by the deflector roll.

5 What I claim as my invention, and desire to secure by Letters Patent, is:

1. In a paper-making machine having co-acting press rolls and a pair of felts co-acting to carry the paper between them through the press, a perforated hollow guide roll interiorly at atmospheric pressure and in contact with one of said felts, said guide roll being located to bring the felts into co-action and deflecting at least one of said felts, whereby only the pressure action imposed by said guide roll against the felts and paper will cause air trapped or carried between the paper and the felt in contact with said guide roll to be pressed out through such felt into the roll perforations and escape to the atmosphere.
2. In a paper-making machine embodying a paper-carrying felt, means for removing air trapped between the felt and paper sheet carried thereby without resort to the use of suction consisting solely of a perforated hollow guide roll engaged by and deflecting the felt, the interior of said roll being always at atmospheric pressure, whereby only the pressure action imposed by said roll against the felt and paper sheet is used to force the entrapped air through the pores of the felt and perforations of the roll to the atmosphere.

35 In testimony whereof, I have signed my name to this application.

WILLIAM H. MILLSPAUGH.
